MACHINE FOR GRINDING THE ENDS OF COILED SPRINGS

Harold Frederick Heath, Redditch, England, assignor to W. J. Llewellyn Limited, Redditch, England

Application July 31, 1947, Serial No. 765,018
In Great Britain July 3, 1946

Section 1, Public Law 690, August 8, 1946
Patent expires July 3, 1966

2 Claims. (Cl. 51—118)

1

This invention relates to a machine for grinding the ends of coiled springs, said machine being of the type having opposed upper and lower grinding wheels mounted on vertical spindles journaled in vertically-adjustable carriages and provided with a feed plate rotatable in a horizontal plane and having spring receiving openings positioned to advance the springs between opposed axially directed faces of the grinding wheels.

The object of the invention is to provide an improved form of supporting structure of frame which enables lateral traversing in the horizontal plane to be effected as between the grinding wheels on the one hand and the feed plate on the other.

In the improved supporting structure or frame according to the present invention, the grinding wheels are so mounted that these are capable of being traversed laterally to adjust the degree of overlap with the feed plate whilst the feed plate is maintained in a fixed position.

One of the major advantages of this arrangement is that in applying the lateral traverse to the grinding wheels this facility is incorporated in the machine without entailing additional complication. It will be appreciated that since the grinding wheels are required to be adjustable in the vertical direction to vary their spacing, the drive to the grinding wheels must in any case be such as to allow this adjustment to take place and therefore by applying the additional facility for transverse adjustment to the grinding wheels. The inherent ability of the drive means to the grinding wheels to admit of bodily adjustment thereof is utilised efficiently in extending the scope of the adjustment which can be carried out.

On the other hand, the feed plate which is normally required to be rotated at a comparatively slow speed such as will permit the insertion of springs into spring receiving openings therein by hand whilst the plate is rotating, is necessarily driven through a reduction gear and consequently the application of the facility for lateral traverse to the feed plate itself would involve considerable complications in the drive mechanism therefor. This is entirely avoided by the present invention.

A further advantage of the invention is that by maintaining the feed plate in a fixed position relatively to the supporting structure of the machine as a whole, the operator always performs precisely the same movement in inserting springs into the feed plate, this factor being of considerable importance in achieving a high productivity with low grade labour.

An embodiment of the present invention will now be described with reference to the drawings in which:

Figure 1 is a view of a machine constructed in

2

accordance with the invention in front elevation.

Figure 2 is a view of the same machine in side elevation viewed from the left hand side of Figure 1.

Figure 3 is a sectional plan view, the section being taken on the line 3—3 of Figure 1.

Figure 4 is a sectional elevational view on the line 4—4 of Figure 3, and

Figure 5 is a fragmentary view in section showing the construction of a feed wheel bush.

The machine is supported by a frame, the lower part of which comprises a table-like top 10 supported at each side by legs 11 themselves connected together at their lower ends by a supporting base plate 12 for a driving motor.

The rear part of the table carries a vertically extending support plate 13 for the grinding wheel motors which is suitably stiffened by means of a longitudinally extending rib 14 at the rear of the plate.

At one side of the table is positioned a bracket which has vertical arms 15 and 16 extending above and below and to one side of the table, each arm terminating in a bearing which carries the feed wheel shaft 17.

The feed plate 18 is supported on and keyed to the shaft 17 and is positioned above the upper bearing 19 at the end of the bracket arm 15. The shaft 17 extends through the lower bearing 20 at the end of the bracket arm 16 and is there provided with a bevel gear 61 engaging the second bevel gear 62 which is driven so as to rotate the feed plate 18.

The feed plate has a number of circular holes 21 spaced around its peripheral margin, the holes extending through the plate with their axes parallel to the feed plate axis.

Each of the holes is provided with a detachable and replaceable bush such as that shown at 22, the internal diameter of which corresponds with the external diameter of the spring which it is required to grind. The bushes are secured by means of grub screws 23 in the feed plate extending radially inwards and accessible from the circumferential edge of the feed plate.

The upper and lower grinding wheel motors 24 and 25 are each supported upon separate upper and lower carriages 26 and 27. The carriages are slidably mounted on the supporting plate 13 by means of a dovetailed rib 28 extending lengthwise along the latter, engaging in grooves of undercut section in the former.

To secure each carriage in position clamping screws 29 and 30 are provided for upper and lower carriages respectively, the inner ends of which force plates such as that shown at 31 interposed between one side of the undercut groove and the dovetailed section rib into clamping engagement with the latter.

In order to permit accurate adjustment of each

carriage and its associated motor and grinding wheel in a vertical direction traversing screws 32 and 33 are provided for upper and lower carriages operated respectively by hand wheels 34 and 35.

The screws 32 and 33 lie within a rectangular section slot cut along the centre of the dovetailed section rib 28 and are prevented from axial movement relative to the supporting plate 13 by means of collars 36 and 37 for the upper screw 32 and by means of collars 38 and 39 for the lower screw 33 disposed on the screws 32 and 33, respectively, on opposite sides of the transverse supporting plate 13 and piece 40, respectively. The ends of the screws remote from the hand wheels pass through internally threaded circular openings in lugs 42 integral with the carriages.

The grinding wheel motors 24 and 25 are positioned so that their spindles lie along the same vertical axis, that of the upper grinding wheel motor projecting in a downward direction and there carrying the upper grinding wheel 43 and that of the lower grinding wheel motor projecting in an upward direction and there carrying the lower grinding wheel 44.

The grinding wheels 43 and 44 have opposed axially directed grinding faces which are spaced from each other by an amount depending upon the length of the springs to be ground and by the amount of metal which it is required to grind from the ends of the springs, the arrangement of the grinding wheels and the feed plate being such that a portion of the feed plate is located between the said faces of the grinding wheels.

Preferably the grinding wheels are rotated in the same direction so that there is no tendency for the springs held in the feed plate to become deflected from the vertical.

Grinding wheels of known construction which may be employed are usually constructed so that an annular grinding element 45 is supported by a metal hub element 46. In order to ensure that full use is made of the available grinding face and further to ensure that when springs of large diameter are being ground portions of these do not project beyond the inner edge of the annular grinding element the centres of the grinding wheels may be adjusted laterally with respect to the centre of the feed plate by means of traversing screw 47 which slides the supporting plate 13 and grinding wheel assembly secured thereon laterally over the top plate 10 of the table so that the said assembly moves in relation to the feed plate 18. Separate traversing screws 47 are provided at each side of the table supported in brackets 48 having threaded circular openings through which screws extend.

The lower grinding wheel motor carriage 27 carries on one side a bracket 49 which serves to support a guide plate 50 for locating and supporting the lower ends of the springs placed in the feed plate. The bracket has a downwardly extending portion 51 provided with slots 52 through which pass securing bolts fastening it to the bed plate, the bracket being capable of vertical adjustment, the securing bolts sliding in the slot, and a second portion 53 of approximately annular form on the upper face of which is carried the lower guide plate 50. The lower guide plate 50 is itself of annular form and has a cut-away portion where it meets the edges of the lower grinding wheel.

The edges 54 and 55 of the cut-away portion of the guide plate are of circular form and have the same curvature as the edge of the lower

grinding wheel and are spaced therefrom by a small clearance.

The upper surface of the lower guide plate is at such a height that it is flush with the upper surface of the lower grinding wheel so that springs guided by the guiding plate pass readily into grinding engagement with the grinding wheel.

In the case of the upper grinding wheel a somewhat similar arrangement is provided comprising an upwardly extending bracket portion 56 secured to the upper carriage 26 and supporting an upper guide plate 57. The upper guide plate 57 is much shorter than the lower guide plate since its function is confined to guiding the upper ends of the springs immediately prior to the entry of these between the grinding wheels.

The upper guide plate 57 has an inclined portion 58, the leading end of which is displaced from the lower guide plate 50 by an amount greater than the length of the springs which it is required to grind, the inclined portion leading to and terminating in a portion which is adjacent the edge of the upper grinding wheel and is there parallel and flush with the lower face of the upper grinding wheel so that the springs can readily pass into grinding engagement with the latter.

The edge of the upper guide plate adjacent the upper grinding wheel is as in the case of the lower guide plate of curved formation and spaced from the grinding wheel by a small clearance.

In order to deliver the springs from the machine when their ends have been ground there is an opening provided in the lower guide plate positioned so that springs carried by the feed plate pass over it after leaving the grinding wheels. Beneath the opening there is provided a chute 59 down which the springs fall into a suitable container.

The drive for the feed plate is derived from an electric motor 60 housed beneath the table and supported upon the bed plate 12, the motor driving the feed plate shaft 17 through a pair of bevel gears 61 and 62 and a preceding reduction gear box 63 and flexible coupling 64.

The motor 60 may also drive a suitable suction device 65 through an endless belt 66, the suction device being connected by a duct 67 to a suitable hood 68 partly surrounding the grinding wheels so that the grinding dust is thereby extracted down the duct. The reduction gear box 63 is such that speed of rotation of the shaft 17 is reduced to a conveniently low value, for example, about four revs. per minute so that an operator can readily insert by hand springs into the openings around the periphery of the feed plate.

In order to re-face the grinding faces of the grinding wheels after these have been in use for a considerable period a diamond facing tool 69 may be provided carried at the end of the pivotal arm 70 secured in a pivotal mounting at one side of the supporting plate 13 so that it can be swung round when required and operate between the grinding wheels, opposite ends of the tool engaging upper and lower faces of the lower and upper grinding wheels respectively.

I claim:

1. In a machine for grinding the ends of coiled springs, the combination of a supporting structure, including a table, bearing means at one side thereof, a vertical spindle supported by said bearing means, a horizontal feed plate mounted on said spindle, said feed plate having spring re-

ceiving openings and extending over said table, means for rotating said feed plate, an upwardly extending carriage support slidably mounted on the upper face of said table for movement towards and away from said spindle, means for effecting and controlling said movement, a pair of vertically spaced carriages slidably mounted on said support, said carriages having respective opposed grinding wheels between which the feed plate extends, means on said carriages for driving said grinding wheels, and said support having means for adjusting and controlling the relative vertical position of the carriages thereon.

2. In a machine for grinding the ends of coiled springs, the combination of a supporting structure, including a table, bearing means at one side thereof, a vertical spindle supported by said bearing means, a horizontal feed plate mounted on said spindle, said feed plate having spring receiving openings and extending over said table, means for rotating said feed plate, an upwardly extending carriage support comprising a base plate slidably supported on the upper face of the table for movement towards and away from said spindle and an upwardly extending bed plate formed with a vertical guide, a pair of vertically spaced carriages slidably mounted on said guide, said carriages having respective opposed grinding wheels between which the feed plate extends, means on said carriages for driving said grinding wheels, means for adjusting and controlling the relative

vertical position of the carriages on the guide, and, a traversing screw device mounted on said table and engaging with said base plate to adjust and control the position thereof with respect to said table, whereby the degree of overlap between the feed plate and the grinding wheels can be varied whilst maintaining the feed plate in a fixed position.
